HEAD FOR COMBINATION SNOW BRUSH AND ICE SCRAPER

Maurice Epstein, 2623 Charney Road,
Cleveland, Ohio 44118

Filed Oct. 10, 1972, Ser. No. 295,877

Term of patent 14 years

Int. Cl. D7—05

U.S. Cl. D7—183

FIG. 1 is a perspective view of the head for combination snow brush and ice scraper;

FIG. 2 is a side view thereof;

FIG. 3 is a top plan view thereof; and

FIG. 4 is a rear view thereof.

The portions of FIGS. 1, 2 and 3 shown in broken lines are for illustrative purposes only and form no part of the claimed design invention.

I claim:

The ornamental design for a head for combination snow brush and ice scraper, as shown and described.
